UNITED STATES PATENT OFFICE.

CHARLES E. DRAKE, OF PLAINFIELD, NEW JERSEY, ASSIGNOR TO CASSANDRA L. MOLLESON, OF NEW MARKET, NEW JERSEY.

FIRE-ESCAPE.

1,282,201.

Specification of Letters Patent.

Patented Oct. 22, 1918.

Application filed March 6, 1916. Serial No. 82,336.

To all whom it may concern:

Be it known that I, CHARLES E. DRAKE, a citizen of the United States of America, and a resident of Plainfield, county of Union, and State of New Jersey, have invented certain new and useful Improvements in Fire-Escapes, of which the following is a specification.

My invention relates to improvements in fire escapes, and particularly to that type thereof intended to be erected outside of a building and opposite a vertical row of windows thereof, and comprising a series of platforms or the like mounted to descend together with means for regulating the descent of such platforms and with means for returning such platforms for further use. According to the preferred embodiment of my invention, these platforms are mounted at suitable intervals upon an endless-chain conveyer supported by a suitable column carrying sprocket wheels over which the chain runs. In connection with the said sprocket chain and the platforms secured thereto, I provide cables movable with the chain and platforms, which cables form convenient hand-grips or rails, movable with the chain and platforms, and which may be grasped by the persons descending on the fire escape, to give them additional security. The chain is provided with suitable guide rollers running in guides provided in the column, and the links of the chain are provided with plates closing the chain-passage between such guides, and so adapted to exclude water, snow, ice, etc., from the chain and chain guides and interior of the column. Suitable means are provided for regulating the tightness of the chain and the tightness of the cables mentioned, and furthermore the cables mentioned are held to the platforms in such manner as to prevent undue slack of the cables, such as might lead to a feeling of insecurity. Brake means, controlled by a hand lever, or by a governor, or both, are provided to regulate the rate of descent of the platforms.

The objects of the invention are to provide a simple and relatively inexpensive fire escape of a nature such that the persons using it have merely to place themselves upon the platforms of the device and may then descend without further effort on their part

and without the dangers and slowness of descent incident to the use of ladders, stairways and the like; and to provide such protection for the persons using the fire escape as will render them secure and will cause them to feel safe during their descent.

I will now proceed to describe my invention with reference to the accompanying drawings, and will then point out the novel features in claims. In said drawings:

Figure 1 shows a side elevation and partial vertical section of one form of fire escape embodying my invention.

Fig. 2 shows a horizontal section of the fire escape.

Fig. 3 shows a fragmentary vertical section of the lower portion of the fire escape, the section being taken on a plane at right angles to that of Fig. 1.

Fig. 4 shows a fragmentary vertical section of a portion of the chain and an attached platform, the platform being in inverted position, as is the case when the platforms are rising.

Fig. 5 shows a front elevation and partial vertical section of the fire escape.

Fig. 6 is a face view of one of the upper cable-pulleys and indicates means for adjusting the tension of the cables independent of the tension of the chain, this tension adjusting means being shown in part in section.

Fig. 7 shows a side elevation of the lower portion of the fire escape, indicating particularly the means for the adjustment of the chain tension, and the means for regulating the speed of descent.

In the drawings, 1 designates a suitable column for supporting the chain and cables, the column being formed, in the particular construction shown, of channel beams 2 and spacers 3 bolted together; this being a convenient construction, whereby a strong and rigid column may be built up from stock structural members. However, I do not limit myself to the construction of the column in this manner, though it is a very convenient and relatively inexpensive construction. At its bottom the column may be supported in any convenient manner upon a suitable base 4; and of course the column may be guyed as desired, though I have not illustrated guy cables. The column is pro-

vided with suitable guide bars 5, forming, with the flanges of the channel bars 2, guide channels in which the pivot bars 6 of the chain links 7 run, these pivot bars being conveniently provided with anti-friction rollers 8 running upon the flanges of the channel bars 2, or upon the guide bars 5, or both, as guides.

To certain of the chain links 7 are secured brackets 9 supporting platforms 10 or other convenient means for holding the persons who are to use the fire escape; I consider that platforms upon which the persons who use the fire escape may stand, are the most suitable means for holding such persons, and contemplate that, in usual practice, the fire escape will be so located that these platforms will pass close to suitable balconies 11 projecting from the building in connection with which the fire escape is located, so that the persons desiring to escape may step directly from these balconies upon the platforms 10. Of course these balconies will, in general, be located in connection with windows or doorways of the building.

The chains 7 pass over suitable sprocket wheels 12, supported by the column 1. One of these sprocket wheels (the lower sprocket wheel, in the construction shown) being mounted upon a shaft 13 carrying a brake wheel 14 having a suitable brake band 15 (Fig. 3 and—in dotted lines—Fig. 7) whereby the rate of movement of the chain may be regulated, and whereby, when desired, the chain may be stopped. For regulating the rate of descent, I may provide a governing device, for example, the fly-ball governor 16 shown in Fig. 7 having connecting links 17, 18 and 19, whereby the governor may apply this brake as necessary; the brake shown being of the familiar expanding type; and one of these links may also be a hand operable lever, whereby when desired the brake may be set up tight so as to arrest the chain. When, as when the fire escape is to be used in connection with a tall building, the column 1 is of considerable height, it is desirable that hand grips shall be provided which the users of the fire escape may grasp in order to give them a feeling of security; and these hand grips should move with the platform. Therefore, I have provided, as such hand grips, cables 20 located at the side of the platforms and passing over rollers 21 which, conveniently, are concentric or nearly so, with the corresponding sprocket wheels 12. I have provided sliding bearings 22 (located, in this instance, near the lower end of the column) for regulating the tension of the chain; and since the lower cable-pulleys 21 are mounted on the same shaft as the lower sprocket wheel 12, adjustment of the chain tension will, to some extent at least, adjust the tension of the cables 20; but since these cables 20 may stretch at a rate different from

that of the chain, I have also provided independent means for the adjustment of the cable tension. This adjustment means is as follows: The shaft 23 for the upper sprocket wheel 12, is a stationary shaft, the upper 70 sprocket wheel 12 revolving around it. The upper cable pulleys 21 are mounted upon bearing blocks 24 having slots 25 (Fig. 6) in which the outer squared ends of the shaft 23 are located. Suitable means, for example 75 screws 26, bearing against the shaft 23, may raise the bearing members 24 more or less, as required, to effect adjustment of tension of cables 20. End plates 27 hold the upper cable pulleys 21, against undue lateral motion on the bearing members 24. Of course I do not limit myself to this particular, or to any particular, means for adjusting the cable tension.

Since, in the case of long cables 20, even 85 if those cables were under considerable tension, they might have considerable sway, unless means to prevent such sway are provided, I pass the cables 20 through suitable apertures in guides 28 with which the individual platforms 10 are provided. These platforms being secured to the chain links, and the chain links themselves being prevented from outward swaying by the flanges of the column 1 and by the guide bars 5, 90 it follows that the cables 20 will be very nearly as rigid as fixed bars would be and so constitute firm grip-members.

It will be apparent that when a person steps upon one of platforms 10, his weight 100 will cause that platform, as well as all other platforms on the same side of the chain, to descend; and should a considerable number of persons occupy several of the platforms simultaneously, too rapid descent will be 105 prevented by the action of the governor controlled brake 15; as each platform nears the ground, the person or persons thereon may jump or step off from the platforms, or, if they do not do so, they will be thrown off by 110 the tilting of the platform incident to its passage around the lower sprocket wheel 12. Each platform, after passing under the lower sprocket wheel, passes up on the other side of the column and, eventually, over the 115 top of the column, and is then available for the descent of other persons. If thought necessary, the chain conveyer may be arrested at any position by setting the brake 15 by hand.

Preferably, and to provide an additional feeling of security for the users of the fire escape, each platform is provided with a rail 29. However, this rail is obviously an unessential element of the device.

In order to inclose substantially completely the channels in which the chain links run, and so to exclude water, snow, ice, etc., from those channels, the chain links preferably are provided with plates 30 running 130

close to the sides of the guide members 5, and so practically inclosing the chain-channels.

What I claim is:

- 5. 1. A fire escape comprising in combination a supporting column and two parallel rows of double-flanged guide bars secured to said column, the flanges of each guide bar extending in opposite directions respectively from the web of that bar, one flange of each such guide bar constituting means for securing the guide bar to the column, the other flange of each guide bar forming with the column a guiding channel, and an 10 endless conveyer mounted on said column and comprising means running in such guide channels and provided at suitable intervals with projecting carriers.
- 15 2. A fire escape comprising the combination with a suitable support and an endless conveyer carried thereby and having carriers projecting from it at suitable intervals, of endless grip cables located in proximity to said carriers, and movable therewith, said grip cables being carried by said support, and being adapted to serve as hand rails.
- 20 3. A fire escape comprising the combination with a suitable support and an endless conveyer carried thereby and having carriers projecting from it at suitable intervals, of endless grip cables located in proximity to said carriers, and movable therewith, said grip cables being carried by said support,

and being adapted to serve as hand rails, 35 said conveyer being guided and thereby held against sway, and said cables being connected to the conveyer and thereby held against sway.

4. A fire escape comprising the combination with a suitable support provided with rotatable sprocket wheels and an endless conveyer carried by said sprocket wheels, and having carriers projecting from it at suitable intervals, of endless grip cables and 40 pulleys therefor likewise carried by said support, and means for moving certain of said pulleys, independent of such sprocket wheels, and in a direction parallel to the longitudinal axis of the column, for adjusting the tension of said grip cables, said grip cables being located adjacent the conveyer and adapted to form hand rails for that conveyer.

5. A fire escape comprising in combination 55 a support having a conveyer channel, an endless conveyer carried by such support and running in such channel, and means carried by the conveyer and movable therewith for substantially closing such conveyer channel.

In testimony whereof I have signed this specification in the presence of two subscribing witnesses.

CHARLES E. DRAKE.
